(57) **CLAIM**

The ornamental design for a foldable pull rod box as shown and described.

DESCRIPTION

FIG. 1 is a top, front and right side perspective view of a foldable pull rod box showing my new design;
FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a top, front and right side perspective view showing the foldable pull rod box in an alternate configuration.

In FIG. 9, the foldable pull rod box is shown with the top cover removed to show aspects of the design that may not be apparent in the other views.

The broken lines in the drawings illustrate portions of the foldable pull rod box which form no part of the claimed design.
